UNITED STATES PATENT OFFICE.

ALF HELMER, OF NEW YORK, N. Y.

KNIFE AND SCISSORS SHARPENER.

1,092,713.

Specification of Letters Patent.

Patented Apr. 7, 1914.

Application filed October 23, 1913. Serial No. 796,844.

To all whom it may concern:

Be it known that I, ALF HELMER, a subject of the King of Norway, and a resident of the city of New York, borough of Brooklyn, county of Kings, and State of New York, have invented a new and Improved Knife and Scissors Sharpener, of which the following is a full, clear, and exact description.

10 This invention relates to improvements in sharpening devices, and particularly to an improved construction which may be used for sharpening knives and scissors.

15 The object in view is to provide a device designed to be adjusted so that either a knife or pair of scissors may be sharpened by an unskilled person.

20 Another object of the invention is to provide a pair of abrading rollers and means for locking the same in an adjusted position, together with means for guiding the blades of a pair of scissors against one of the rollers.

25 In carrying out the object of the invention a frame is provided in which a pivotally mounted stationary roller is arranged. These rollers are made of abrading material of any desired kind, as for instance stone, carborundum, steel, or other desired material. A notch is provided in the frame for accommodating a knife, whereby the same may be drawn across the rollers, that is, drawn across both rollers simultaneously, the opposite sides of the knife engaging opposite rollers. Arranged adjacent one of the rollers is a guiding member for the blades of a pair of scissors, said guiding member being associated with an adjustable brace, whereby the guiding members may be 30 adjusted so as to give any desired angle to the scissors.

35 In the accompanying drawing—Figure 1 is a top plan view of a sharpening device embodying the invention, part of the same being broken away for better illustrating the adjustable features of one of the rollers; Fig. 2 is a side elevation of the structure shown in Fig. 1; Fig. 3 is a section through Fig. 1 on line 3—3; Fig. 4 is a detailed fragmentary bottom plan view showing how one side of the frame is mortised in place.

40 Referring to the accompanying drawing by numeral 1 indicates a base provided with sides 2 and 3. Preferably, side 3 is made

removable, as shown in Figs. 2 and 4. Bottom 1 is provided with an extension 4 mortised into the side 3, which side is held in place by suitable retaining screws 5. By making side 3 removable the various parts of the sharpener may be removed and again applied without any considerable trouble.

45 Arranged above base or bottom 1, and supported by sides 2 and 3 are abrading rollers 6 and 7 which may be formed of any desired material, as for instance a granular matter or a roughened steel. The rollers are preferably provided with graduations 8 and 9, respectively, which co-act with the indicating marks 10 and 11, whereby the rollers may be gradually rotated and present new 50 surfaces to the knife 12. In order to prevent the rollers from rotating when the device is in use locking screws or set screws 13 and 14 are provided which press against the respective rollers and lock the same 55 against rotation. In order that a short edge or a longer edge may be provided for knife 12 roller 7 is arranged adjustable, and the pintles 15 are mounted in apertures 16 in the sides 2 and 3. Adjusting screws 17 and 18 are provided for limiting the movement of roller 7 from roller 6. The operating handles of the screws 17 and 18 are arranged in suitable notches 19 in the sides 2 and 3, whereby they do not project beyond the end 60 of the device but slightly from the sides thereof.

65 Arranged on the end of the device opposite the screws 17 and 18 is a guiding device 20 for properly holding scissors or shears in place when sharpening the same. A guiding plate 21 is pivotally mounted in the sides 2 and 3, and is held at any desired angle by a bracing member 22 formed so that the lower end may engage notches 23 70 in the base or bottom 1.

75 In operation one blade of the shears 24 is positioned as shown in Fig. 3 and drawn back and forth across the roller 6. If it should be desired to give a greater or less angle to the bevel of the blade member 22 may be adjusted as desired. When sharpening the knife 12 if a short edge is desired the rollers are arranged as shown in Fig. 3, but if a longer edge is desired the rollers are 80 separated and the knife 12 is drawn across through the notches 25 and 26, whereby the knife will engage the rollers 6 and 7. As

the knife is ground away roller 7 is gradually adjusted or moved toward roller 6 so as to bring the edge to a proper finish.

What I claim is—

- 5 1. In a device of the character described, a base, a pair of up-standing members, a fixed abrading roller, means for locking said fixed abrading roller in any desired position, an adjustable abrading roller arranged to 10 co-act with the first mentioned abrading roller, said up-standing members being formed with slots for accommodating the supporting shaft of said adjustable abrading roller, a pair of set screws for said shaft, 15 for moving said adjustable abrading roller toward the first mentioned abrading roller, and means for locking said adjustable abrading roller against rotation.
2. In a device of the character described, 20 a housing formed with upstanding side members having alined notches, an abrading roller arranged on each side of said notches journaled in said upstanding members, graduations arranged on each of said rollers, 25 an index mark arranged on one of said up-standing members and co-acting with the

graduations on said abrading rollers, clamping members for preventing the rotation of said rollers and means for adjusting one of said rollers toward and from the other roller 30 without interfering with the action of said graduations and said index mark.

3. In a device of the character described, a base, a pair of up-standing members connected to said base, an abrading roller journaled in said up-standing members, a pivotally mounted guide arranged adjacent said abrading member for holding a tool to be sharpened, a pivotally mounted arm connected to the outer end of said pivotally mounted 40 guide, and a plurality of stops engaging the end of said arm opposite that connected with said guiding member, whereby said guiding member may be adjusted to different angles.

In testimony whereof I have signed my name to this specification in the presence of two subscribing witnesses.

ALF HELMER.
